REMOVABLE BLADE SCRAPER

Wayne W. Perry, 2291 Kendall St., Edgewater, Colo.

Filed Oct. 18, 1965, Ser. No. 87,563

Term of patent 3½ years

(Cl. D9—6)

FIG. 1 is a perspective view of a removable blade scraper embodying my new design.

FIG. 2 is a bottom plan view of the removable blade scraper.

FIG. 3 is a top plan view of the removable blade scraper.

FIG. 4 is a side-elevational view of the removable blade scraper; and

FIG. 5 is a rear-elevational view of the removable blade scraper.

It is to be understood that the surface ornamentation shown partially omitted in FIGS. 1 and 3 of the drawing covers the entire area encompassed thereby.

I claim:

The ornamental design for a removable blade scraper, substantially as shown and described.
